UNITED STATES PATENT OFFICE

PARIS R. FORMAN, OF RAHWAY, NEW JERSEY, ASSIGNOR TO NATIONAL PNEUMATIC COMPANY, OF NEW YORK, N. Y., A CORPORATION OF WEST VIRGINIA

SWITCH

Original application filed January 29, 1931, Serial No. 511,952. Divided and this application filed July 24, 1931. Serial No. 552,903.

This invention relates to improvements in switch structures as will be described in detail below.

The switch of this invention is particularly adapted for use with, but is not necessarily limited to use with, a system such as disclosed in my copending application Serial No. 511,952, filed January 29, 1931, Patent No. 1,874,483, issued August 30, 1932, for "Door operating mechanism", of which this application is a divisional application.

One of the objects of this invention is to provide a switch mechanism which is partially controlled by means of a key.

A still further object of this invention is the provision of a switch which may be operated manually in one direction when released by a key to a position at which it remains. The switch may be manually operated from that position to a second position, from which it automatically returns to a third position when released. The switch may be operated from the third position to the second position without the use of a key.

These and many other objects as will appear from the following disclosure are attained by means of this invention.

This invention resides substantially in the combination, construction, arrangement and relative location of parts, all as will be described in greater detail below.

Referring to the drawings:

Figure 1 is a front outside elevational view of the switch of this invention;

Fig. 2 is a cross-sectional view taken on the line 2-2 of Fig. 1;

Fig. 3 is an enlarged front elevational view of the switch with the cover removed and a portion thereof broken away;

Fig. 4 is an enlarged detailed elevational view;

Fig. 5 is a developed view of the contact on the drum of the switch;

Fig. 6 is an exploded perspective view of the details of the locking and actuating mechanism including the switch drum operated thereby;

Fig. 7 is a detailed front elevational view of a portion of the mechanism showing the

operating key and its action on the parts operated thereby;

Fig. 8 is a view of a suitable key for unlocking the switch.

This invention will be described in detail in connection with the drawings from which its nature and operation will best be understood. As shown in Figs. 1 and 2 the switch comprises a base-plate 11 over which fits a cover 1 having a raised central portion 2 to provide a housing for the parts. This raised portion 2 is provided with a projecting hood 3 in which are located buttons 4 and 5 for operating switches within the casing. At 6 is a removable plate which is provided with a keyhole 7. This plate forms part of the cover portion 2. Screws 8 are provided for securing the cover 1 to the base-plate 11. Screws 9 are provided for mounting the complete structure on any suitable support. 10 represents the handle by means of which the switch mechanism is operated in part, or in a counter-clockwise direction.

Referring to Fig. 2 it is noted that the raised portion 2 of the cover is provided with internally projecting bosses 10' in which the push buttons slide. The boss is so formed and the push buttons are so formed as to provide recesses within which springs 11' are provided for resisting depression of the buttons. Secured to the cover with the buttons are contact strips 12. At 15 is a standard secured to the base-plate on which is secured a block of insulating material 14. Secured to this insulating block in spaced relation are the contacts 13 arranged in alignment with the contact strip 12. The switches controlled by both push buttons 4 and 5 are the same in construction. When either push button is depressed its spring is compressed and the contact strip 12 controlled thereby is moved to bridging position with respect to the fixed contacts 13 to complete circuits connected thereto.

At 16 is a bracket having a transverse bar 17 which is secured to the base-plate by means of screws 17'. The other end of bracket 16 is provided with a ring-shaped member 18. Secured to each side of the bracket are blocks of insulating material 19 which have

two right angled parallel walls of insulating material 20. Secured on the right-hand block 19 (see Fig. 3 in connection with Fig. 2) are three contact fingers 21, 22 and 23. These contact fingers, as well as the corresponding contact fingers 34, 35 and 36, are arranged so as to pivot upon the metal strips 25 secured to the insulating blocks. The spring fingers are held in position by means of pins 24 secured in the metal bars 25 and projecting through the spring fingers. Compression springs encircle these pins and engage the spring fingers to permit their swinging outward about their pivot points under the resilient reaction of the springs.

At 26 is a shaft which is journaled in the base-plate at one end and which is provided at the other end with a disc 33 rotatably supported in the ring 18. Mounted on shaft 26 for rotation therewith is a drum of insulating material 27 upon which is supported a contact plate 28. The shape of the contact plate is shown in Fig. 5 in development, although when applied to the drum it assumes a curved form. Secured to shaft 26 for rotation therewith is a short arm 29 which is mounted so that in its movement it engages with the vertically slidible rod 30. This rod is slidably supported in bearing 31 and a hole in the bar 17. This rod is encircled by a spring 32 which lies against bar 17 and collar 31' which is secured to rod 30. Thus, when arm 29 engages rod 30 and pushes it upwardly, it does so against the reaction of spring 32. At 37 is a stop secured to the base-plate to limit, by its engagement with arm 29, the clockwise rotation of shaft 26 and drum 27.

Disc 33 is generally circular in outline and is rotatably supported within ring 18. As stated above, this disc is secured to the forward end of shaft 26 and performs, as one function, a support therefor. The shaft 26 is square and fits into a square central opening in the disc to effect continued rotation. This disc is also cut away on the lines 39, as shown.

Secured to the disc is a projecting pin 38 which has a function to be described later. Disc 33 is provided for a limited portion on its periphery with a groove 40 which extends completely across its thickness. A complementary, but slightly longer groove 41 is cut in ring 18, which groove does not extend all the way through the thickness of the ring, as is clear from the drawings. Within a suitably shaped hole in disc 33, with the axis of the hole parallel to the sides of the disc, is a pin 42 which projects beyond the edge 39 and is provided with a head 43. Secured to the periphery of ring 18 is a long spring 44 which is provided at its free end with a pin 45 which projects through ring 18 and contacts with the rounded end of pin 42.

As is clear from Fig. 3, the pin or lug 45, in

the position which spring 44 normally holds it, projects into the path of notch 40 to limit the clockwise rotation of disc 33, shaft 26, and drum 27. However, when pin 42 is moved inwardly it forces lug 45 out of the path of notch 40 so that disc 33, shaft 26 and drum 27 may be given a clockwise rotation. Whether or not the lug is in locking position, disc 33 may be given counter-clockwise rotation.

Referring to Figs. 2 and 4, it will be seen that the circular plate 6 secured to the face of the raised portion 2 of the cover is provided with a semi-circular integral ring portion 50 which holds the plate 6 in spaced relation with the portion 2 of the cover. The central portion of disc 6 projects inwardly, as shown at 53, in conical form. This conical portion is cut away to provide the key-hole 7. The plate 46, which is formed integral with the handle 10, is provided with two arcuate portions 51 and 52 (Fig. 4) which have an external diameter approximately the same as the internal diameter of the opening in the casing projection 2. These arcuate lugs form a centering and rotating surface for the arm 10 and its integral plate 46 so that all of these parts may be revolved. The plate 46 is cut away centrally so that the conical central portion 53 of the outer disc 6 projects therethrough. The lugs 51 and 52 are on a circle indicated by the dotted lines 61 in Fig. 4. The conical portion 53, which projects through plate 46, terminates along the dotted line 60 in Fig. 2. Lug 38 on disc 33 lies between the arcuate lugs 51 and 52 so as to be in their path of movement. Thus when the handle 10 is moved to the right (Fig. 4) the right-hand end of lug 52 engages the pin 38 and causes disc 33, drum 27, and arm 29 to rotate in a counter-clockwise direction against the resistance of spring 32.

The relationship and structure of the operating parts including the locking mechanism is clearly shown in Fig. 6.

It should be noted, as is clear from Fig. 6 and Fig. 7, that the arcuate notch 40 on the surface of disc 33 terminates at one end in a right angled shoulder 95 which cooperates with the flat end of pin 45 so as to positively lock the disc 33 and the parts connected thereto against clockwise rotation (Fig. 7) when the pin 45 is in normal position. Thus, unless the pin 45 is pushed to the position shown in Fig. 7 by the pin 42, it is impossible to rotate the disc 33 in clockwise direction from the position shown in Fig. 3. The arcuate notch 40 in the disc 33 is provided so that the disc and the parts movable therewith may be rotated in counter-clockwise direction even when pin 45 is in normal position projecting through the ring. The arcuate groove 41 in the ring 18 is provided so that disc 33 can be rotated in a clockwise direc-

tion even if the pin 42 is projecting to the position shown in Fig. 7 under the action of the key. The pin 42 is only returned to the normal position shown in Fig. 3 when the disc moves back to a point where the projecting pin 42 strikes the pin 45. Fig. 7 clearly shows the manner in which the wing 100 of the key 90 cooperates with the head 43 of the pin 42.

When a proper key is inserted in keyhole 7 and the key is rotated clockwise the tongue of the key bears against pin 42 and thus forces lock 45 out of the path of disc 33. A further clockwise rotation of the key rotates disc 33, shaft 26, and drum 27 from their normal position until arm 29 (Fig. 2) strikes the stop 37. For purposes of description the position to which drum 27 has been rotated is referred to as the "second position". The key can then be withdrawn without causing any rotation of disc 33. The parts will remain in this second position until returned by application of force to handle 10. When force is applied to handle 10 its integral lug 52 bears against pin 38 and thus causes disc 33, drum 27, and arm 29 to rotate counter-clockwise. When this rotation has proceeded in a counter-clockwise direction to the normal position pin 45 under the pressure of spring 44 drops into groove 40 and disc 33 and thus prevents clockwise rotation of disc 33, drum 27, and arm 29 until a proper key has again been used. The said counter-clockwise rotation can be carried further by the application of force to handle 10 though such further rotation is yieldingly opposed by rod 30 and spring 32 bearing on arm 29. The full counter-clockwise movement of handle 10, disc 33, and drum 27 is reached when arm 29 is stopped by striking bearing 31 which is integral with the base 11. This position of drum 27 and the handle 10 is hereinafter referred to as the "third position" of the switch.

The pressure of spring 32 on rod 30 and against arm 29 is such as to rotate in a clockwise direction arm 29, drum 27, disc 33, and handle 10 when pressure is released from handle 10 until this rotation is stopped by disc 33 striking pin 45. The travel of rod 30 and spring 32 is limited by collar 31 striking bearing 31 but sufficient travel is provided so that disc 33 is held against pin 45 thus keeping drum 27 in its normal position until pin 45 is forced out of the path of disc 33 as above described or until pressure is applied to handle 10 in a counter-clockwise direction. It is apparent that handle 10 may be used to rotate disc 33 and drum 27 from the normal position to the "third position" without the use of a key.

A feature of the construction as herein described is that as bracket 16, insulating blocks 19, contact fingers 21, 22, 23, 34, 35 and 36, shaft 26, drum 27, the contact piece

on drum 27 and the disc 33 as well as block 14 and contacts 13 are carried by base 11, the cover 1 may be removed from the switch without distorting the connections to the contacts, the alignment of the shaft 26 and disc 33 in the supporting bearings on the base-plate and in ring 18, the alignment of drum 27 with respect to the contact fingers nor the positions of the drum 27 as determined by stops 37, 45 and 31.

The removal of the cover carries with it as a unit assembly the push buttons 4 and 5, the escutcheon plate and the operating handle.

From the above description it will be apparent that this invention resides in certain principles of construction and operation which may be embodied in other physical forms, and I do not, therefore, desire to be strictly limited to the disclosure as given for purposes of illustration, but rather to the scope of the appended claims.

What I seek to secure by United States Letters Patent is:

1. An article of manufacture as described comprising a supporting casing, a ring-shaped member supported in said casing, a shaft journaled at one end in the casing, a disc mounted on the other end of the shaft and journaled in said ring, a switch drum mounted on said shaft, a contact mounted on the drum, contact fingers mounted in said casing and cooperating with the contact on the drum, resilient means mounted on said ring and cooperating with said disc for preventing rotation of the disc, drum and shaft in one direction, key operated means for moving the resilient means to a position to free the disc, shaft and drum for operation in one direction, and handle actuated means for operating the disc, shaft and drum in the opposite direction independently of the resilient locking means.

2. An article of manufacture as described comprising a supporting casing, a ring-shaped member supported in said casing, a shaft journaled at one end in the casing, a disc mounted on the other end of the shaft and journaled in said ring, a switch drum mounted on said shaft, a contact mounted on the drum, contact fingers mounted in said casing and cooperating with the contact on the drum, resilient means mounted on said ring and cooperating with said disc for preventing rotation of the disc, drum and shaft in one direction, key operated means for moving the resilient means to a position to free the disc, shaft and drum for operation in one direction, and manually operable means journaled in said casing and cooperating with said disc for operating the disc, shaft and drum in the opposite direction independently of the resilient means.

3. An article of manufacture as described comprising a supporting casing, a ring-

shaped member supported in said casing, a shaft journaled at one end in the casing, a disc mounted on the other end of the shaft and journaled in said ring, a switch drum mounted on said shaft, a contact mounted on the drum, contact fingers mounted in said casing and co-operating with the contact on the drum, resilient means mounted on said ring and cooperating with said disc for preventing rotation of the disc, drum and shaft in one direction, key operated means for moving the resilient means to a position to free the disc, shaft and drum for operation in one direction, a lug mounted on said disc, and manually operable means journaled in said casing and co-operating with the lug on said disc when operated in one direction to rotate the disc, shaft and drum in the same direction independently of the resilient means.

4. An article of manufacture as described comprising a supporting casing, a ring-shaped member supported in said casing, a shaft journaled at one end in the casing, a disc mounted on the other end of the shaft and journaled in said ring, a switch drum mounted on said shaft, a contact mounted on the drum, contact fingers mounted in said casing and co-operating with the contact on the drum, resilient means mounted on said ring and cooperating with said disc for preventing rotation of the disc, drum and shaft in one direction, key operated means for moving the resilient means to a position to free the disc, shaft and drum for operation in one direction, handle actuated means for operating the disc, shaft and drum in the opposite direction independently of the resilient locking means, a plurality of circuit terminal means mounted in said casing, and a plurality of manually operable contact members mounted in said casing for interconnecting said terminals.

5. A switch structure as described, comprising a support, a ring member secured to said support, a shaft journaled at one end in said support, a disc secured to the other end of said shaft and journaled in said ring, a switch contact drum mounted on said shaft, a plurality of contact fingers mounted on said support for cooperation with the switch contact drum, a cover secured to said support for closing all of said parts, and manually operable means journaled in the cover and cooperating with said disc for rotating the disc, shaft and drum in one direction.

6. A switch structure as described, comprising a support, a ring member secured to said support, a shaft journaled at one end in said support, a disc secured to the other end of said shaft and journaled in said ring, a switch contact drum mounted on said shaft, a plurality of contact fingers mounted on said support for cooperation with the switch contact drum, a cover secured to said support

for closing all of said parts, manually operable means journaled in the cover and co-operating with said disc for rotating the disc, shaft and drum in one direction, a lug movably mounted on said ring and projecting therethrough, said disc having a peripheral groove into which the lug projects and cooperates to prevent rotation of the disc in one direction, and means mounted on the disc for forcing the lug out of the groove, said manually operable means cooperating with said disc to rotate the disc, shaft and drum in the opposite direction when the lug is thus forced out of the groove.

7. A switch structure as described, comprising a support, a shaft journaled on said support at one end, a bearing member mounted on said support in which the other end of the shaft is journaled, a switch drum mounted on said shaft, a plurality of contact fingers cooperating with the switch drum mounted on said support, means cooperating with said shaft for preventing its rotation in one direction, a cover for the parts forming with said support a substantially closed casing, manually operable means journaled in said cover and cooperating with said shaft for rotating the shaft in either direction, the manually operable means being free to rotate the shaft in one direction at any time, and key operable means engageable with the means preventing the rotation of the shaft in one direction to free the shaft for rotation by the manually operable means in the opposite direction.

8. A switch structure as described, comprising a supporting plate, a shaft journaled at one end in the plate, a ring-shaped bearing member secured to the plate, a disc journaled in the ring and mounted on the other end of the shaft, a switch drum mounted on the shelf for rotation therewith, a plurality of contact fingers mounted for cooperation with the switch drum, a lever mounted on said shaft, resilient means engageable by the lever for resiliently resisting the rotation of the disc, drum and shaft in one direction, locking means mounted on the ring and cooperating with the disc for preventing its rotation in one direction, key operable means mounted on the disc for moving the locking means to a position to free the disc for rotation in one direction, a cover forming with said plate a substantially closed casing, a disc having a handle and a pair of arcuate shoulders on one face thereof, said shoulders being journaled in the cover to permit rotation of the disc, and means secured to the disc mounted on the shaft and cooperating with the shoulders on the second disc whereby the first disc, shaft and drum are rotatable with the second disc.

9. A switch structure as described, comprising a substantially closed casing, a shaft journaled at one end in the casing, an aper-

tered bearing member in the casing, a disc secured to the other end of the shaft and rotatably mounted in the apertured bearing member, manually operable means journaled in the casing and cooperating with said disc for rotating the disc and shaft in either direction, a contact drum mounted on the shaft, a plurality of contact fingers cooperating with the contact drum, and key operable means cooperating with the disc for preventing rotation of the disc, shaft and drum in one direction, said disc, shaft and drum being releasable for operation in that direction by a key insertable in the casing.

10. A switch structure as described, comprising a substantially closed casing, a shaft journaled at one end in the casing, an apertured bearing member in the casing, a disc secured to the other end of the shaft and rotatably mounted in the apertured bearing member, manually operable means journaled in the casing and cooperating with said disc for rotating the disc and shaft in either direction, a contact drum mounted on the shaft, a plurality of contact fingers cooperating with the contact drum, key operable means cooperating with the disc for preventing rotation of the disc, shaft and drum in one direction, said disc, shaft and drum being releasable for operation in that direction by a key insertable in the casing, a lever mounted on said shaft, and a spring control member cooperating with said lever for resiliently resisting movement of the disc, shaft and drum in the opposite direction and for returning the disc, shaft and drum to normal position.

11. In a switch structure as described, the combination comprising a plurality of contact fingers, a contact drum rotatably supported adjacent said fingers, locking means for preventing rotation of the drum in one direction, manually operable means for operating the drum in either direction, resilient means for resisting rotation of the drum in one direction, and for returning it to normal position when freed, the locking means limiting the rotation of the drum by the resilient means, and key operable means for releasing the locking means so that the drum may be operated in the opposite direction by the manually operable means.

In testimony whereof I have hereunto set my hand on this 21st day of July, A. D. 1931.

PARIS R. FORMAN.
